UNITED STATES PATENT OFFICE.

CARL A. ANDERSON AND ANDREW A. ANDERSON, OF WORCESTER, MASSACHUSETTS.

TOOL-REST FOR GRINDING-MACHINES.

1,206,791.

Specification of Letters Patent.

Patented Dec. 5, 1916.

Application filed March 6, 1916. Serial No. 82,455.

To all whom it may concern:

Be it known that we, CARL A. ANDERSON and ANDREW A. ANDERSON, citizens of the United States of America, residing at 5 Worcester, in the county of Worcester and State of Massachusetts, have invented certain new and useful Improvements in Tool-Rests for Grinding-Machines, of which the following is a specification, reference being 10 had therein to the accompanying drawing.

This invention relates to tool rests for grinding machines and has for its principal object the production of a simple and efficient means for obtaining a very accurate 15 adjustment for the supporting element of the tool which is being sharpened so that the tool may be brought into engagement with the emery stone in any position desired owing to the edge which may be desired 20 upon the tool.

Another object of this invention is the production of tool rests for grinding machines wherein the tables employed are mounted so as to permit their elevation to 25 be changed independent of their supports, while their supports are also capable of being swung, whereby various angles may be assumed by the tables so that the tools positioned thereon may have their edges brought 30 into engagement with and easily ground by the emery stones so as to form an edge of a desired shape upon the tool which is being sharpened.

Another object of this invention is the 35 production of a tool rest for grinding machines wherein the tool rests are pivotally supported upon a supporting bar, while the table of each tool rest is pivotally mounted upon a rod carried by the frames, so that 40 two adjustments may be obtained for each tool rest, as there is means provided for releasably retaining the tables in set positions, thereby permitting the tool to be brought 45 into engagement with the emery wheel at any angle desired.

With these and other objects in view this invention consists of certain novel combinations, constructions, and arrangements of parts as will be hereinafter fully described 50 and claimed.

In the accompanying drawings: Figure 1 is a front elevation of the tool rest for a grinding machine, showing the complete device, and illustrating the manner in which 55 the same is used. Fig. 2 is a top plan view

of the tool rest for grinding machines. Fig. 3 is a vertical section taken on the line 3—3 of Fig. 1, looking in the direction of the arrow. Fig. 4 is a front elevation of one of the tool rests, illustrating the manner in 60 which the detachable elongated tool rest is carried upon the table. Fig. 5 is a section taken on the line 5—5 of Fig. 3. Fig. 6 is a section taken on the line 6—6 of Fig. 1, showing the tool clamp in section mounted 65 upon the table. Fig. 7 is a section taken on the line 7—7 of Fig. 1. Fig. 8 is a section taken on the line 8—8 of Fig. 4. Fig. 9 is a section taken on the line 9—9 of Fig. 4. Fig. 10 is a section taken on the line 10—10 of Fig. 2. Fig. 11 is a sectional view, partly 70 in elevation, illustrating the manner in which the worm gear is supported upon one of the frames of one of the tool rests. Fig. 12 is a horizontal section taken on the line 75 12—12 of Fig. 1. Fig. 13 is a perspective view, partly broken away, of the side of a detachable tool rest, used in connection with this invention. Fig. 14 is a top plan view of a detachable tool clamp to be mounted 80 upon one of the tables.

Referring to the accompanying drawings by numerals it will be seen that 1 designates a hollow casing which is adapted to be carried upon any suitable support or machine 85 support 2. This casing 1 has a rotating shaft 3 carried by its upper portions upon which the pulleys 4 are keyed, while adjacent its ends there are carried the emery wheels 5 within the hoods 6. Any suitable source of 90 motor power may be applied to the pulleys 4 so that as the pulleys 4 rotate rotary motion will be imparted to the emery wheels 5, as the shaft 3 is rotated.

It is not deemed necessary to deal more 95 specifically with the construction of the grinding machine *per se* inasmuch as the invention deals more particularly with the tool rests which are adapted to hold the tools which are being mounted in position to be 100 engaged by the emery stones 5.

The integral supporting lugs 7 are formed upon the forward ends of the casing 1 in parallel spaced relation as disclosed most clearly in Figs. 1 and 2. The bar 8 passes 105 through these lugs 7 and is held against rotation and retained in a set position by means of the set screws 9 which are carried by the lugs 7 and engage the bar 8. This bar 8 extends for a considerable distance be- 110

yond the side surface of the lugs 7 and beyond the ends of the casing 1 so as to extend to a point in alinement with the emery stones 5. Each tool rest comprises a frame 5 which consists of a split sleeve 10 having depending flanges 11 formed upon its lower portions through which extend the screws 12 of the grip 13. Thus, it will be seen that as the grip 13 is swung in one direction it 10 will draw the flanges 11 toward each other, thus causing the sleeve 10 to bind upon the bar 8 and thus hold the frame in a set position. From the extreme end of the frame there extend the integral fingers 14 which 15 diverge toward their upper ends and which have the collars 15 formed integral thereon upon their upper ends. The short rod 16 is carried by the collars 15 of each frame and is held in a fixed engagement therewith by 20 means of the set screws 17 which pass through these collars and into a binding engagement with the rod 16. One of the tables 17' comprises an elongated plate upon its upper surface which has a depending lug 18 formed 25 upon one end thereof, which is pivotally or rotatably mounted upon the inner projecting end of one of the rods 16. The split lug 19 is formed integral upon the table 17' adjacent its opposite end and has its split ends 30 extending for a distance below the rod 16. The screw 20 of the grip 21 passes through the lower ends of this split lug 19 so that upon rotating in one direction the split lug will be drawn together so as to bind 35 positively and firmly upon one rod 16, thus holding the table 17' in an adjusted set position. It will be seen that if it is desired to obtain a very sharp edge upon the tool which is to be sharpened the grip 21 may be rotated so 40 as to cause the split lug to release this binding action. The table 17' may then be swung upwardly at its forward edge or the edge which is adjacent the emery wheel or stone 5, and then the grip 21 may be rotated so 45 as to tighten the split lug upon the rod 16. The grip 13 of this particular frame may then be rotated so as to cause the sleeve to release its binding action upon the bar 8 and then the frame may be swung toward 50 the emery wheel so as to allow the inner edge of the table 17' to be positioned adjacent the emery wheel and at an elevated plane, after which the grip 13 may bind the sleeve upon the bar. The tool may then be positioned 55 upon the table and because of the angle at which the table extends, such for instance as a plane of approximately 45°, the edge formed upon the tool will be similar to the edge formed upon a chisel or plane. If it is 60 desired to form an edge upon some instrument such for instance as a scissors the grip 13 may be rotated so as to cause a binding action of the sleeve 10 upon the bar to be released, at which time the frame may be 65 swung away from the emery wheel to any

position desired. The table 17' upon the actuation of the grip 21 may be turned to extend nearly in a horizontal plane and then one blade of the scissors may be positioned upon the table and moved into engagement 70 with the emery wheel or stone so as to obtain a very sharp cutting edge which, of course, is somewhat differently formed from the ordinary cutting edge of the ordinary tool. The table 22 has a journal lug 18' 75 which is mounted upon the rod 16 of the remaining frame. At the opposite end of this table 22, however, there is carried an integral depending body 23 having a rack 24 formed on its periphery. A curved neck 25 extends from one of the fingers 14, extending to one side thereof, as shown in Figs. 1 and 11. This neck 25 has a sleeve 26 formed integral thereon, through which the stem 27 passes. The grip wheel 28 is keyed by 80 means of the sleeve 29 upon one end of this stem 27, while the worm gear 30 is shrunk or secured in any other manner upon the opposite end of the stem 27. This neck 25 is formed upon one of the fingers 14 so that 85 the worm gear 30 will mesh with the rack 24 upon the body 23. Thus, it will be seen that as the grip wheel 28 is rotated, rotary motion will be imparted by means of the stem 27 to the worm gear 30 and this action 90 will cause the rack 24 to move the body and thus swing the table 22 to different planes upon the rod 16 upon which the same is mounted. Thus, it will be seen that besides obtaining the adjustment of the sleeve 10 of 95 this particular frame the table 22 may further be adjusted as is the case with the table 17' by means of the worm screw and grip wheel. It is, of course, obvious by referring particularly to Fig. 1 that the split lugs of 100 the two tables are carried so as to bear against the outer side surface of the collars 15 formed upon the fingers 14, thereby holding the tables from longitudinal movement 105 upon the rods under any circumstances. 110

It will be seen that the table 22 is provided with a beveled forward face 31, while there is formed adjacent its rear edge the longitudinal upstanding rib 32. There is also formed upon the forward beveled edge 115 of the table 22 a plurality of beveled integral blocks 33.

The elongated detachable tool rest as disclosed in Fig. 13 comprises an elongated body 34 having the depending lugs 35 formed upon its lower surface, which lugs 35 have beveled inner portions 36. When this detachable rest is used it is positioned upon the upper surface of the table 22 so as to allow the lugs 35 to engage the blocks 120 33 of the table. There is provided upon the rear portion of this detachable rest 34 a side flange 37 having a depending lip 38 formed thereon, in which there is carried a screw 39. When this detachable rest is 125 130

positioned upon the table 22 the lugs 35 will engage the blocks 33 as above stated and since the blocks 33 and lugs 35 are beveled they will be held from having accidental upward movement. At this time the screw 39 may be rotated so as to engage the beveled rear face 40 of the table 22 thus holding the detachable rest against accidental displacement. This detachable rest 10 is comparatively long so that tools having long edges to be sharpened may be positioned thereon and may be moved therewith into engagement with one of the emery stones or wheels 5.

15 The clamp disclosed in Fig. 14 comprises a body 41 having the ribs 42 formed upon its lower surface so as to ride easily upon the upper surface of the tables. When used in connection with the table 22 it is obvious that it will rest against the rib 34 of this table and thus be guided evenly along the upper portions of the table 22. The machine faces 43 of the body 41 are formed at a distance below the overhanging lip 44 in which there is carried a set screw 45. Thus, it will be seen that a tool as indicated at 46 may pass beneath the lip 44 so that the set screw 45 may be brought into engagement therewith for positively holding the tool in engagement with the body 41. As this tool clamp is mounted upon the table 22, the table, of course, may be adjusted so as to allow the tool to be brought into engagement with the emery wheel 5 for obtaining the correct cutting edge upon the tool. As the emery wheel is rotated it will be seen that the tool clamp 41 may move back and forth upon the upper portions of the table 22, whereby the entire cutting edge of the tool may be sharpened.

It is obvious that it is necessary to pivotally support the frame of each table because of the fact that if only the table were pivotally mounted when swung upwardly or downwardly at its forward edge it would be swung away from the stone to such a distance as to make it impossible for the tool to engage the same. By having the frame of each table mounted so as to be moved toward or away from the stone as necessary, it is obvious that when the forward edge of the table is swung upwardly the frame may be moved toward the stone so as to engage the edge of the table adjacent thereto, or when the forward edge of the table is swung downwardly the frame may be swung away from the stone for providing sufficient space to accommodate this action or movement of the table.

60 From the foregoing description it will be seen that very simple and efficient tool rests for grinding machines have been provided, which can be positioned upon almost any form of grinding machine, simply by providing supporting lugs or blocks upon the casing

of the machine adjacent the emery wheels upon which the frames and tables may be supported by means of a fixed bar. It is further obvious that as these frames are provided with simple means for retaining the same in set positions after being swung to a desired position and owing to the fact that simple and efficient means has been provided whereby the tables may be adjusted independent of the movement of the frames, the tables may be moved to assume desired angles so that as the tools are positioned thereon they will extend in any desired angle for correctly engaging the emery wheels.

80 What is claimed is:

1. In a tool rest for grinding machines, the combination of a support, lugs carried upon said support, a bar carried by said lugs, means for holding said bar in engagement with said lugs, said bar extending beyond said lugs, frames carried upon the projecting ends of said bar, means for holding said frames in an adjusted set position, tables adjustably mounted upon the upper portions of said frames, said frames being capable of being swung for moving said tables and said tables being capable of moving independent of said frames, whereby said tables may be moved to desired positions when in use.

2. In a tool rest for grinding machines, the combination of a support, a bar carried by said support, a frame carried by said bar, said frame comprising a sleeve, said sleeve being split and having outwardly extending flanges extending from points adjacent its split portion, means for drawing said flanges together for binding said sleeve upon said bar, upwardly extending fingers carried by said sleeve, and a table adjustably mounted upon the upper end of said fingers, said table being capable of being moved independent of the movement of said frame, and said frame also being capable of being moved to accommodate said table for permitting the table to be swung to a desired position when in use.

3. In a tool rest for grinding machines, the combination of a support, a bar carried by said support, a frame carried by said bar, said frame comprising a sleeve, said sleeve being split and having outwardly extending flanges extending from points adjacent its split portion, means for drawing said flanges together for binding said sleeve upon said bar, upwardly extending fingers carried by said sleeve, collars formed upon the upper ends of said fingers, a rod carried by said collars, said rod extending beyond the side portions of said collars, a table pivotally mounted upon said bar, means for holding said table in an adjusted set position, said frame being capable of being moved in unison with said table, said table being capable

of being moved independent of said frame, whereby the table may be moved to a desired position when in use.

4. In a tool rest for grinding machines, the combination of a support, a frame adjustably mounted upon said support, a neck carried by said frame, a stem carried by said neck, a worm gear carried upon said stem, a grip wheel carried by said stem, whereby said stem may be rotated for turning said worm gear, a table pivotally mounted upon the upper portions of said frame, a body formed upon said table having a rack formed upon its periphery, said rack engaging said worm gear, whereby as said worm gear is rotated by said grip wheel, said table may be swung to assume different positions, and said frame also being capable of being moved in unison with said table.

5. In a tool rest for grinding machines, the combination of a support having lugs formed thereon, a bar carried by said lugs, a split sleeve carried by said bar, means for drawing said sleeve together for binding upon said bar, outwardly extending fingers carried by said sleeve, a neck extending from one of said fingers, a stem carried by said neck, a worm gear carried upon said stem, collars formed upon the upper ends of said fingers, a rod carried upon said collars, a table having a depending lug carried upon one end of said rod, a body formed upon the opposite end of said table and engaging the opposite end of said rod, whereby said table will be pivotally supported, a rack formed upon the periphery of said body and engaging said worm gear, whereby said sleeve may be loosened so as to permit said frame to move to an adjusted position after which said sleeve may be clamped upon said

bar, after which the grip wheel will cause said worm gear to cause said body to move said table independent of said frame so as to cause the table to assume a desired position when in use. 45

6. In a tool rest for grinding machines, the combination of a support, lugs carried by said support, a bar carried by said support, a split sleeve carried by said bar having flanges extending therefrom, a screw carried by said flanges for causing said sleeve to be bound upon said bar, outwardly extending fingers extending through said sleeve, collars carried upon said fingers, a rod carried by said collars, means for holding said rod against accidental displacement, a table having a lug supported upon said rod, a split lug engaging said rod adjacent its opposite end, and means for drawing said lug into binding engagement with said rod, whereby said table may be retained in a set position.

7. In a tool rest for grinding machines, the combination of a table, means for adjustably supporting said table, said table having beveled blocks formed upon its forward edge and having a beveled rear edge in combination with a detachable tool rest fitting thereon, said detachable rest having depending lugs formed integral thereon, said lugs having beveled faces fitting upon the beveled faces of said blocks, a flange formed upon said detachable rest having a depending lip, a set screw carried by said lip and engaging the beveled edge of said table, whereby said detachable rest will be held against accidental displacement. 70

In testimony whereof we hereunto affix our signatures.

CARL A. ANDERSON.
